UNITED STATES PATENT OFFICE.

CHARLES WOTRUBA, OF FORT WASHINGTON, PENNSYLVANIA, ASSIGNOR TO CHARLES L. BACHMAN AND EUGENE HAHN, BOTH OF PHILADELPHIA, PENNSYLVANIA, COMPOSING THE COPARTNERSHIP VICTOR ENGINEERING CO.

ASH CONVEYER AND EJECTOR.

Application filed August 21, 1922. Serial No. 583,234.

My invention relates to conveyers and ejectors of the steam jet, vacuum or similar type, which convey or move ashes, coke or other disintegrated material through a duct by the force of vacuum or pressure created through the medium of fluids such as steam or air sent through this duct at high velocities and attending expansions. In conveyers or ejectors of this type where there is a bend in the duct, or where the course of the ashes in the duct is changed, it is common practice to employ detachable liners disposed at the point of impingement of the material against the side of the duct and adapted, after having been worn to the maximum amount, to be removed and replaced by others, thereby preventing wear in the duct itself or part thereof.

The object of this invention is to provide improved means for securing these liners in place, this securing means being such as to eliminate all possibility of displacement of the liners which would be bound to interfere with the satisfactory and efficient operation of the conveyer or ejector.

The invention will be more readily understood by reference to the attached drawings, in which:

Figure 1, is a transverse section through that section of an elbow in the duct in which the nozzle, by means of which the fluid jet is formed, is established;

Fig. 2, is a section on the line 2—2, Fig. 1, and

Fig. 3, is a view in perspective of the wedge-like key.

In the drawings, 1 indicates a section of an ejector duct, in the present instance substantially L-shaped and in the form of an elbow, having in one side an opening 2 for insertion of a nozzle 3, which latter is disposed in substantial alignment with the center line of one leg 4 of the duct, as best illustrated in Fig. 1. At the outer edge of each of the legs, 4 and 5, of the section are provided flanges 4^a and 5^a respectively constituting means for attaching thereto the similarly flanged ends of other duct sections, not shown. In the type of duct to which this elbow belongs, steam is commonly employed as the actuating medium, a jet of steam discharging from the nozzle upwardly through the leg 4 of the duct and having the effect

of drawing inwardly through the leg 5 ashes or other materials deposited in that section of the ejector and forcing them outwardly through the leg 4. As the ashes or other materials are drawn into the leg 5 of the duct, the momentum of their movement carries them against the rear wall of the leg 4, this portion of the duct wall accordingly receiving the considerable impact and thus the heaviest wear and normally deteriorating with much greater rapidity than the remainder of duct constituting the conveyer or ejector.

It has been customary in the past to line such elbows and bends of the duct wall with detachable elements adapted to take the wear and to be replaced when sufficiently worn. As clearly shown in Fig. 2, the liner elements 6 are in the present instance substantially semicircular in cross section, although they may be of various other shapes, and either straight sided or curved according to the needs of the particular application or the design of that portion of the duct to which the liner is applied, with one face recessed at 7 to conform to the curvature of the interior of the duct, these liners being received in a pocket 8 at the rear of the leg 4 of the section 1, said pocket being provided with a detachable cover plate 9 for retaining the liner elements therein. Bolts 10 in the present instance secure the cover plate to the section 1, and a suitable gasket 11 is provided to make the joint tight.

As best illustrated in Fig. 2, the cover plate has in the present instance inwardly extending lugs or projections 12 which are adapted to bear against the rear faces of the liner elements, which are thus confined between the said projections and a pair of shoulders 13, 13, at the inner side of the pocket 8, against which the forward side edges of the liner elements bear, as best shown in Fig. 2.

As shown in Fig. 1, two main liner sections 6, 6, are employed, one end face of each of the sections being square with the sides, although they may be of any desirable shape, and the other end surface of each of the liners lying at a slight angle. In this elbow 1, these liner sections are disposed as shown in Fig. 1, with the square ends abutting shoulders 14, 14, at the top and bottom of the pocket in which the liners are established,

the inclined faces at the opposite ends of the liners forming therebetween a wedge-shaped opening in which a securing wedge or key 15 is established, said key being clearly illustrated in Fig. 3. The key 15, which in the present instance functions as a section of the liner, has extending from its rear face studs 16, 16, adapted to pass through the cover plate and having nuts, whereby the key may be drawn tightly between the two liner sections, spreading said sections apart and forcing them against the aforesaid shoulders 14, 14, of the pocket. It will be seen that in this manner the sections of the liner are most firmly secured in the pockets, the forward edges of the liners bearing against the longitudinal shoulders 13, 13, at the front of the pocket, the rear face of the liners bearing against the lugs 12 on the cover plate and the wedge-shaped key forcing the said liners respectively against the end shoulders 14, 14, of the pocket. In a construction of this type, there is no possibility of the liners becoming loosened and dislocated under the severest impact of material against such liners opposing their direction.

It will be noted that the liner sections 6, 6, have exactly the same dimensions and are accordingly reversible, the one section being capable of taking the position of the other section, and vice versa. In this manner, any uneven wear developing in the sections may be evened up by changing the positions of the sections.

It will be apparent that the principle of this invention may find application at any point in the duct where there occurs a change in direction and where in fact there occurs an impingement of the material passing through the duct against the side thereof. It will further be understood that there may be considerable modification in the form of the liners and in the number of sections and keys employed, these not being limited to the number illustrated in the drawings and hereinbefore described.

I claim:

1. A duct having a liner so established therein as to constitute a section of the duct wall, said liner comprising a plurality of sections placed end to end longitudinally of the duct, shoulders on said duct abutting the ends of the liner, and a wedge-shaped key disposed intermediate adjacent ends of the sections and adapted to hold the sections in place between the said shoulders.

2. A duct having therein a liner so established as to constitute a section of the wall of the duct, said liner comprising a plurality of sections disposed end to end longitudinally of the duct, the ends of the liner being square with the sides of the sections, and the adjacent ends of the sections being formed at an angle to the sides and being

so disposed relative to each other that a substantially wedge-shaped opening is formed therebetween, shoulders in said duct abutting the said square ends of the liner, and a wedge-shaped key established between the adjacent ends of the sections and constituting means for retaining the said sections in place between the shoulders.

3. A duct having a detachable liner so established therein as to constitute a section of the duct wall, said liner comprising a pair of independent sections each of which has one end square with the longitudinal side edges and the other end formed on an angle thereto, a pocket in said duct in which the liner sections are established end to end longitudinally of the duct and with the inclined end faces adjacent each other, shoulders at the ends of the said pocket constituting abutments for the square ends of the sections, and a wedge-shaped key established between the inclined adjacent end faces of the sections and adapted to force the sections outwardly against the said shoulders.

4. A duct comprising a pocket adapted to receive a liner constituting a section of the duct wall, said liner comprising a plurality of sections adapted to be placed end to end in the pocket longitudinally of the duct, a cover plate for said pocket, means for securing the cover plate to the duct, a wedge-shaped element adapted to be established intermediate adjacent ends of the respective sections, and means for securing said wedge-shaped element to the said cover.

5. A duct comprising a pocket adapted to receive a liner, said liner comprising a plurality of sections adapted to be placed end to end in said pocket longitudinally of the duct to constitute a section of the duct wall, shoulders in said duct forming an abutment for the front side edges of the liner sections, a cover for said pocket adapted to be secured to the duct and forming an abutment for the rear side of the liner sections, shoulders forming abutments for the ends of said liner, and a wedge-shaped key adapted to be established between adjacent ends of the liner sections for confining the liner sections tightly between the said end shoulders.

6. A duct having a liner established therein to constitute a section of the wall of the duct, said liner comprising main sections disposed end to end longitudinally of the duct, and a wedging key section established intermediate adjacent ends of the main sections, substantially as and for the purpose set forth.

7. A duct having a liner established therein to constitute a section of the wall of the duct, said liner comprising a plurality of sections disposed end to end longitudinally of the duct, abutments upon the duct for the

outer ends of the liner sections, and means for confining the sections under compression between said abutments.

8. A duct having a liner established there-
5 in to constitute a section of the wall of the
duct, said liner comprising a pair of
sections placed end to end longitudinally
of the duct, abutments on the duct for the
outer ends of said sections, and means estab-
10 lished intermediate the adjacent ends of said
sections for forcing the latter longitudinally
against said abutments.

9. A duct having a liner established there-
in to constitute a section of the wall of the
duct, said liner comprising a pair of end 15
sections and an intermediate section longi-
tudinally of the duct, abutments on the duct
for the outer ends of said sections, said
intermediate section being adapted by in-
sertion between the adjacent ends of the end 20
sections to force the latter outwardly against
the abutments.

CHARLES WOTRUBA.
